PICTURE FRAME

Bruno C. Roehrl, Erie, Pa., assignor to National Organ Supply Company, Erie, Pa., a corporation of Pennsylvania

Application April 1, 1947, Serial No. 738,538

6 Claims. (Cl. 40—156)

1

In picture frames of cast or molded thermoplastic material there is a tendency of the material to cold flow or warp causing the frame to draw away from the glass. These effects are accentuated if the back fastening produces points of stress concentration. Other stresses causing cold flow may result from hinges connecting two or more frames. This invention is intended to overcome these difficulties by a back fastening and hinge construction which minimizes localized stress.

In the accompanying drawing, Fig. 1 is a rear view of a picture frame; Fig. 2 is an enlarged view showing one of the removable corner pieces; Fig. 2a is a view showing one of the other corner pieces; Fig. 3 is a perspective of removable corner piece; Fig. 4 is a section on line 4—4 of Fig. 2; Fig. 5 is a front view of two frames hinged together, and Fig. 6 is a section showing the hinge construction and the connection of the hinge straps to the frames.

Referring to the drawing, there is shown a rectangular picture frame having sides 1 and ends 2 sloping rearwardly from the front of the frame toward the outer edges. On the rear face of the frame is a ledge 3 for receiving a glass 4, a picture 5, and a back 6 which may be provided with an easel 7. At the outer periphery of the ledge 3 are side and end rails 8 and 9 projecting from the rear face of the frame beyond the back. The glass is held against the ledge by corner pieces 10 and 11 at the lower and upper corners of the frame. The corner pieces 11 are provided with tongues 12 receivable in slots 13 at the junctions of the side and end rails and tongues 14 receivable in slots 15 in the side and end rails. The upper corner pieces 11 can be molded integral with the frame or can be molded separately and cemented in place. It is not necessary that the upper corner pieces be removable as the picture, glass, and back can be slid under the corner pieces. Each of the lower corner pieces 10 has a central flexible tongue 17 having its outer end 18 extending through the slot 13 at the junction of the side and end rails and having on the projecting end a detent ridge 19 engaging the outside of the corner and securely holding the corner piece in place.

As shown in Fig. 3, the tongue 17 is bowed upwardly to increase the holding effect of the detent ridge 19. The flexibility of the tongue 17 is increased by cut out portions 20 on either side. The greatest stress on the tongue 17 arises as the tongue is being pushed through the corner slot 13. As soon as the detent ridge 19 moves

2

through the corner slot, the stress on the tongue 17 is relieved. Cold flow accordingly will not move the detent ridge away from the locking or holding position.

On either side of the central tongue 17 are short tongues 21 receivable in the slots 15 in the side and end rails. At one side of the tongues 21 are stop surfaces 22 which locate the corner pieces. Insertion and removal of the corner piece is made easier if a downward pressure is exerted on the tongue 17 at the same time that an inward or outward pressure is exerted on a rib 23.

Two or more frames may be connected at adjacent edges by hinges as shown in Fig. 5 to stand as a unit. The hinges comprise flexible straps 24 having at one end a knuckle joint 25 connected by a hinge pin 26 and having at the other end a projection 27 receivable in a hole 28 in the corner pieces 10 and 11. Each of the knuckle joint members has an integral hook 29 which overlaps the outer edge of the frame. In effect the hooks 29 are provided by a slight undercut 30. A similar undercut 31 is provided on the projections 27 which conforms with the conical sides 32 in the openings 28.

In the assembly, the hooks 29 are placed over the outer edge of the frame and a downward pressure exerted at the center of the flexible straps 24. This causes the projections 27 to snap into the holes 28. The undercuts 30 and 31 relieve the stress in the hinge straps and at the same time provide a secure fastening.

The frame is adapted to casting from thermoplastic material with the rails integral with the sides and ends of the frame. The slots 13 and 15 may be molded in the rails. The corner pieces 10 and 11 and the hinge straps 24 may be made of the same material. While thermoplastic material is obtainable in a wide variety of attractive colors, it is subject to warping and to cold flow. It is therefore desirable that localized stress be avoided. This is accomplished in the present construction by the corner pieces and by the hinges, both of which are designed to minimize localized stress in the frame.

What I claim as new is:

1. A frame for pictures and the like having a ledge on its rear face for receiving a glass and back, side and end rails bounding the ledge and extending rearwardly from the frame, slots in the side and end rails and at a corner or junction between the side and end rails, a corner piece for holding the glass against the ledge having a portion resting on the back with edges engaging the rails and tongues received in the slots, the

tongue receivable in the corner slot projecting through the slot and having detents cooperating with the outer surface of the rails to yieldably resist removal.

2. A frame for pictures and the like having a ledge on its rear face for receiving a glass, side and end rails bounding the ledge and extending rearwardly from the frame, slots in the side and end rails and at a corner or junction between the side and end rails, a corner piece for holding the glass against the ledge, a portion resting on the back with edges engaging the rails and tongues received in the slots, the tongue receivable in the corner slot having its free end bowed away from the ledge and projecting through the slot and having detents cooperating with the outer surface of the rails to yieldably resist removal.

3. A frame for pictures and the like having a ledge on its rear face for receiving a glass, side and end rails bounding the ledge and extending rearwardly from the frame, a retainer cooperating with a rail to hold the glass against the ledge, said retainer having a hole, and a hinge member having a portion at one end hooked over the outer edge of the frame and a projection at the other end snapped through the hole in the retainer.

4. A frame for pictures and the like having a ledge on its rear face for receiving a glass, side and end rails bounding the ledge and extending rearwardly from the frame, a retainer cooperating with a rail to hold the glass against the ledge, said retainer having a hole, and a hinge member having projections at opposite ends respectively overlapping the outer edge of the frame and extending through the hole in the retainer, said projections having undercuts providing hooks.

5. A frame for pictures and the like having a ledge on its rear face for receiving a glass, side and end rails bounding the ledge and extending rearwardly from the frame, slots in the side and

end rails and at a corner, a corner piece for holding the glass against the ledge having integral tongues receivable in the slots, the tongue receivable in the corner slot projecting through the slot and having detents cooperating with the outer surface of the rails to yieldably resist removal, said corner piece having a hole, and a hinge member having projections at opposite ends respectively overlapping the outer edge of the frame and extending through the hole in the corner piece, said projections having undercuts providing hooks.

6. A frame for pictures and the like having a ledge on its rear face receiving a glass, a rail bounding the ledge, a slot in the rail, a retainer having a portion resting on the back with an edge engaging the rail at one side of the slot, a tongue on the retainer projecting through the slot and having a detent cooperating with the outer surface of the rail to yieldably resist removal, said tongue and slot, when the retainer is rested on the back in position to slide along the back toward the rail, being aligned in the direction of movement of the retainer.
